NAPKIN HOLDER CONSTRUCTION

Carl B. Sundberg, Meriden, Conn., assignor to The International Silver Company, Meriden, Conn., a corporation of Connecticut

Filed Sept. 16, 1959, Ser. No. 840,352

7 Claims. (Cl. 211—50)

This invention relates to an improved holder for table napkins and the like.

The primary object of this invention is to provide a napkin holder for supporting a pack of napkins in an upright lobately folded condition and enabling one or more of said napkins to be readily removed from the holder without disturbing the remaining napkins.

Another object of this invention is to provide a napkin holder of the above type which presents a pleasing appearance and supports the pack of napkins in a decorative configuration.

The above and other objects and advantages of this invention will be apparent from a reading of the following description with reference to the accompanying drawing in which:

Fig. 1 is an isometric view of a napkin holder embodying this invention;

Fig. 2 is a plan view of the napkin holder; and

Fig. 3 is a section taken along line 3—3 of Fig. 2.

In Fig. 1 a napkin holder embodying this invention is shown supporting a pack of napkins 2 in an upstanding condition. As indicated, the holder is integrally formed of sheet material such as metal, plastic, wood, and the like, and includes a body portion 4 and supporting legs 5. The body 4 of the napkin holder is defined by upright walls formed into a trifoliate shape providing a rearwardly opening front or center chamber or pocket 6 and two generally forward opening rear or side chambers or pockets 8. As shown in Fig. 1 of the drawing, the napkin pack is supported by the holder in a lobately folded U-shaped configuration without crimping or creasing the napkins. The folded portion 10 of the napkin pack is disposed in the central chamber 6 and opposite upright edges 12 of the napkins are received within the side chambers of the holder.

Looking at Fig. 2 the holder body 4 comprises a front wall 14 and side walls which include rearwardly extending generally parallel portions 15 and outwardly diverging portions 18 forming an obtuse dihedral angle with the parallel portions. From the outer edges of the diverging walls 18 the body 4 further includes rearwardly converging walls 20 and forwardly and inwardly extending walls 22 which are generally parallel to the diverging walls 18 and terminate in laterally spaced relation opposite the front chamber 6. The side wall portions 15 and 18 fair together in concavely curved wall portions 24 disposed intermediate the front and rear chambers and having radii r located outwardly of the body of the holder.

The front chamber 6 is generally U-shaped being defined by the front wall 14 and the side wall portions 15. The side wall portions define an opening facing toward the center of the holder. The rear chambers 8 are defined by the outwardly diverging side wall portions 18 and the walls 20 and 22. The rear chambers are also of generally U-shaped configuration opening generally toward the center of the holder. It will be noted that the opening of the front chamber is approximately twice

2

as large as the openings of the rear chambers to freely accommodate the fold of the napkin pack without creasing the napkins.

The length of the side walls from the front chamber 6 to each of the rear chambers is approximately equal to half the width of the napkin pack. When the napkin pack is disposed within the holder as shown in Fig. 1, opposed outer surface portions of the napkin pack, intermediate the fold 10 and the upstanding edge portions 12, are engaged by the curved wall portions 24 and a curvature such as indicated at 26 is imparted to the napkin pack. Inner surface portions of the pack adjacent the upright edges 12 are engaged by the walls 22, the upright edge portions are thus held in outwardly diverging relation. The walls 22 thus bend or fold the side portions of the napkin pack around wall portions 24 and increase the upright rigidity of the pack which is, in effect, held by the holder in a corrugated condition.

As seen in the drawing, the holder is open at its top 20 whereby the napkin pack may be grasped along its side edges 12, folded into generally U-shape, and inserted downwardly into the holder. The side edges are inserted in the side pockets and the folder is received in the center pocket.

Even though the napkins are rigidly retained in upright condition, the chambers of the holder are of sufficient size to loosely receive both the folded and upright edge portions of the napkin pack. This reduces the intersurface friction of the napkins of the pack and enables one or more of the napkins to be easily removed from the holder without disturbing the remaining napkins.

The body portion of the holder is supported in spaced relation to an underlying surface by means of the legs 35 5. The legs are in the form of tabs which are curved inwardly from the lower edge portions of the front wall 14 and inwardly extending walls 22. These tabs provide legs for the napkin holder and assist in retaining the napkins within the body of the holder permitting the holder to be moved from place to place without dropping its contents.

Preferably the holder is made of deformable sheet metal. In such case an additional advantage may be gained in enabling the user to adjust the disposition of the containing side walls of the device to vary the grip or pressure thereof against opposing halves of the napkin pack. In this way various sizes of napkin packs or napkins of different paper material can be attractively displayed to insure the straight upright condition thereof 50 in the holder. That is to say the opposed curved portions at 24 (Fig. 2) may be brought closer together to increase the ability of the holder to support the pack in an upright condition. This may be done without sacrificing or seriously impairing the advantageous characteristics of the holder as previously described particularly with respect to the inter-surface friction between individual napkins. Deformation of the holder as described would be particularly desirable where the holder will be normally used for a small number of napkins or where 55 the composition of the napkin material is of an abnormally limp character. Where an unusually thick pack of napkins is placed in the holder it may, of course, be desirable to spread the walls 15 apart to an extent greater than shown by the substantially parallel condition seen in Fig. 2 to accommodate the larger size. The walls 22 may, of course, also be bent outwardly relative to opposing walls 18 of the rear pockets 8 to vary the extent of divergence of the upstanding edge portions of a pack. It should be noted, however, that the free edges of the 60 walls 22 should preferably remain in a spaced relation substantially approximating the spacing between the curved wall portions 24.

Having described this invention what is claimed is:

1. A napkin holder comprising a body defined by upright walls of sheet material formed into a trifoliate shape for holding a pack of napkins in edgewise, upright and lobately folded condition, said body including three upright chambers having opposed openings, one of said chambers being of sufficient size to receive the folded portion of the pack without creasing the napkins, the others of said chambers being disposed relative to said one chamber to receive the opposite upright edge portions of the folded napkin pack and hold said edge portions in outwardly divergent relation.

2. A napkin holder comprising an integral body defined by upright walls of sheet material formed into a trifoliate shape for holding a pack of napkins in edgewise, upright and lobately folded condition, said body including a center chamber and two side chambers extending the height of said walls, said chambers including opposed openings extending throughout their height, said center chamber being of sufficient size to receive the folded portion of the napkin pack without creasing the napkins, said body including side wall portions defining in part said side chambers and disposed in outwardly diverging relation to said center chamber, the distance between each of said side chambers and said center chamber being approximately equal to one-half the width of said napkin pack whereby said side chambers receive the upright edge portions of the folded napkin pack and hold them in outwardly diverging relation when the folded portion of the pack is disposed in said center chamber.

3. A napkin holder comprising an integral body defined by upright walls of sheet material formed into a trifoliate shape for holding a pack of napkins in edgewise, upright and lobately folded condition, said body including a center chamber and two side chambers extending the height of said walls, said chambers including opposed openings extending throughout their height, said center chamber being of sufficient size to receive the folded portion of the napkin pack without creasing the napkins, said body including side wall portions defining in part said center chamber and side wall portions defining in part said side chambers and diverging outwardly at an obtuse angle to the side wall portions defining said center chamber, the distance between each of said side chambers and said center chamber being approximately equal to one-half the width of said napkin pack whereby said side chambers receive the upright edge portions of the folded napkin pack and hold them in outwardly diverging relation when the fold of the pack is disposed in said center chamber, the angled portion of said side walls being engaged with opposite side portions of said napkin pack intermediate the fold and upstanding edge portions thereof and imparting an upright corrugation thereto which increases the upright rigidity of said pack.

4. A napkin holder comprising a body defined by upright walls of sheet material formed into a trifoliate shape for holding a pack of napkins in edgewise, upright and lobately folded condition, said body including a center chamber and two side chambers extending the height of said walls, said chambers being generally U-shaped and opening toward each other, said center chamber being of sufficient size to receive the folded portion of the napkin pack without creasing the napkins, said body including side wall portions defining in part said center chamber

and side wall portions defining in part said side chambers and diverging outwardly at an obtuse angle to the side wall portions defining said center chamber, the distance between each of said side chambers and said center chamber being approximately equal to one-half the width of said napkin pack whereby said side chambers receive the upright edge portions of the folded napkin pack and hold them in outwardly diverging relation when the folded portion of the pack is disposed in said center chamber, the angled portion of said side walls being engaged with opposite side portions of said pack intermediate the fold and upstanding edge portions thereof and imparting an upright corrugation thereto which increases the upright rigidity of said pack, and legs in the form of tabs extending downwardly and inwardly from lower edge portions of said upright walls.

5. A napkin holder for supporting a pack of napkins in folded relation with the pack standing on one edge, said holder comprising a body open at its top and defined by upright walls shaped to provide an upright center and two side pockets extending the height of said walls and of generally U-shaped configuration opening toward one another, said body including side walls defining in part the center and side pockets thereof, the portions of said side walls defining the side pockets being disposed in outwardly diverging relation to the portions of the side walls which define the center pocket, the distance between each side pocket and the center pocket being approximately half the width of the pack of napkins to be supported by said holder whereby said pack may be grasped along opposed side edges folded into generally U-shape and the side edges inserted into the side pockets with the intermediate folded portions of the pack being received in the center pocket.

6. A napkin holder comprising a body for supporting a pack of napkins in edgewise, upright and lobately folded condition, said body comprising opposed upright wall portions spaced to engage opposed outer surface portions of said pack intermediate the fold and upright edge portions thereof and wall portions positioned to engage inner surface portions of said pack adjacent its upright edges and disposed outwardly of said opposed wall portions sufficiently to bend the side portions of said pack around said opposed wall portions thereby imparting upright rigidity to said pack.

7. A napkin holder for supporting a pack of napkins in edgewise, upright and lobately folded condition and comprising supporting means to support the lower edge of the pack, opposed upright portions extending upwardly from said supporting means and spaced to engage opposed outer surface portions of said pack intermediate the fold and upright edge portions thereof, and upright portions positioned to engage inner surface portions of said pack adjacent its upright edges and disposed outwardly of said opposed portions sufficiently to bend the side portions of said pack around said opposed portions, thereby imparting upright rigidity to said pack.
